UNITED STATES PATENT OFFICE.

WILLIAM D. MARTIN AND HENRY SCHRIK, OF CHICAGO, ILLINOIS.

COMBINED METAL PANEL AND DOOR CONSTRUCTION.

1,304,343.

Specification of Letters Patent.

Patented May 20, 1919.

Application filed June 9, 1917. Serial No. 173,717.

To all whom it may concern:

Be it known that we, WILLIAM D. MARTIN and HENRY SCHRIK, both citizens of the United States, and residents of Chicago, 5 in the county of Cook and State of Illinois, have invented new and useful Improvements in Combined Metal Panel and Door Constructions, of which the following is a specification.

10 This invention relates to a combined metal panel and door frame for the inlet end of ice-intake openings provided in walls of dwelling houses and apartments.

15 Among the objects of our invention is to provide a combined panel and door frame for the purpose referred to, and which may be made as a complete and distinct unit before being installed in an ice-intake opening. Other and further objects of our invention will more fully appear in the following description.

20 In the accompanying drawings:

Figure 1 is a front elevational view of a portion of a building wall and having applied in the ice-intake opening thereof a combined metal panel and door frame constructed in accordance with our invention;

Fig. 2 is a vertical sectional view taken on line 2—2 of Fig. 1;

30 Fig. 3 is a horizontal sectional view taken on line 3—3 of Fig. 1;

Fig. 4 is a horizontal sectional view taken on line 4—4 of Fig. 2; and

Fig. 5 is a vertical sectional view taken on line 5—5 of Fig. 3.

As has been the construction heretofore in connection with ice-intake openings, the latter are made just large enough to permit the easy passage therethrough of the largest 40 block of ice usually delivered to dwelling houses and apartments, and as a result the wall continued downward between the bottom of such openings and the floor of the room in which the ice-box is located. In

45 most apartments as now built and being built, the ice-box or refrigerator is located in the pantry, and the latter is made relatively small. With a portion of the wall between the bottom of the ice-intake opening and the floor of the pantry, the latter is

50 necessarily and unduly crowded when the average sized ice-box or refrigerator is placed therein with its rear or back wall against the inner face of the building wall and over said opening. In some cases, the portion of the building wall between the

bottom of the ice-intake opening and the floor of the pantry is cut away or reduced in thickness so as to provide a niche or recess in which the ice-box is placed so that the 60 latter will not project out into the room to an undue extent. But even in such a case the ice-box projects into the room to an unnecessary extent. As the building wall in the average case is not over twelve inches 65 in thickness, it is apparent that an ice-box or refrigerator of the average size could not be completely set back in the wall. To do so would require the building of a wall of a thickness greater than the width of 70 the average ice-box, which of course would be impracticable for many reasons. It is the purpose of our invention to make the ice-intake opening of such a nature as to permit the ice-box to be set in the wall 75 to the maximum extent possible, and thus prevent the ice-box from occupying any more of the pantry than absolutely necessary. The manner in which we accomplish this is shown in the accompanying drawings. 80

As illustrated in said drawings, 10 indicates a building wall such as the outside wall of a pantry of a dwelling house or an apartment. Said wall is provided with an ice-intake opening 11 extending therethrough and 85 opening at one end on the outside of said wall and at the other end into the pantry, if such is the room in which the ice-box or refrigerator is located. Said opening 11 extends vertically between the floor 12 of the 90 pantry and the window 13, usually provided therein. Of course the upper end of said opening 11 terminates short of the bottom or sill of said window, there being a portion of the wall between such parts. The 95 bottom of said opening 11 terminates at and forms a continuation of the floor 12. The sides of the opening 11 are parallel and vertically straight, and the opening is of such size as to permit the entire ice-box 15 to 100 be pushed therethrough, if such would be required. The bottom of the opening 11 terminates above the floor 16 of the back porch, as shown, for it is a universal practice to have the floor of the porch lower 105 than the floor of the kitchen and pantry.

Placed in the outer end of the wall opening 11 is a cast metal panel 17, the latter being of such size as to completely cover said opening. Said panel is provided with 110 an inwardly extending, integral flange 18 completely surrounding the same and ex-

tending into the opening 11. Said flange 18 has top, bottom, and side portions, all of the same width and thickness and bearing substantially flatwise against the corresponding portions of the wall opening 11. Said panel is provided on the outside thereof with a marginal flange 19 completely surrounding the same and extending over the outer edges of the wall opening 11. Said marginal flange 19 bears substantially flatwise against the outer face of the wall 10 about the opening 11 therein, and imparts the necessary finish thereto, as best shown in Fig. 1. Said panel 17 is provided in the upper half there-
 15 of with a doorway or rectangular opening 20, which is normally closed by a metal door 21, the latter constituting the outer door of the ice-intake opening proper. Said door 21 is preferably hinged along one of its
 20 side or vertical edges to the panel 17. The hinge means includes a hinge rod 22 extending vertically across the back of the door, as shown in Fig. 3. Said rod is secured to the rear face of said door by clamp
 25 straps 23. As shown in Fig. 3, the side portion of the outer marginal flange 19 along the hinged side edge of said door extends over such edge. At the lower edge of said door the panel 17 is provided with an in-
 30 wardly extending integral flange 24, which extends into the opening 11 to the same extent as the flange 18. The hinge rod 22 extends above and below the top and bottom edges of the door 21, and has its ends
 35 in sockets (not shown) in the upper portion of the flange 18 and the lower flange 24, in somewhat the same manner as disclosed in Letters Patent No. 1,224,766, granted May 1st, 1917.
 40 Said door 21 is countersunk or set back in the panel so that its outer face will be substantially flush with the outer surface of said panel, the portions of the flanges 18 and 24 about the edges of the door being so
 45 formed as to accomplish such purpose. On the outside of the door and adjacent its non-hinged side edge is secured a handle 25. The door 21 is locked closed and unlocked from the ice-box side of the wall 10 by a
 50 locking mechanism such as shown in and claimed in our Patent No. 1,258,132, granted March 5, 1918, and needs no further mention herein, except that the latch part of such mechanism is carried by the door and is in-
 55 dicated herein by the reference numeral 26, the keeper by 27, and the pull cord by 28.
 The ice-box 15 is pushed into the opening 11 until its rear or back wall comes practically into contact with the inner edges
 60 of the flanges 18 and 24. The rear casters 29 of the ice-box rest on the bottom wall of the opening 11, while the front casters 30 rest on the pantry floor 12. The waste water from the refrigerator 15 may be caught
 65 in a drip pan placed beneath the same, or a

waste pipe extending through the floor may be provided, neither of which has been shown on account of being so obviously well known. As shown in Figs. 2, 3, and 5, the ice-box is provided in its rear wall with a 70 door 31 employed for closing the doorway opening into the ice chamber, said door 31 being opened when it is desired to deposit ice in said ice-box from the outside of the wall 10. As shown in Figs. 3 and 5, said 75 door 31 is hinged along one side of the ice-box by hinges 32, 32, and is provided adjacent the other side with a combined handle and latch 33.

Many houses and apartments have been 80 robbed by the thief entering the house through the ice-intake opening, the outer door being pried or forced open and then the ice-box being pushed into the room and away from the ice-intake openings by the 85 thief applying the necessary force against the rear of the ice-box from the outside of the wall. In order to guard against this as far as possible, we secure the ice-box to the metal panel 17, which in itself is fixed in the 90 wall opening 11. To secure the ice-box to the panel, there is provided a metal frame 34, made of integrally connected angle-bars, as shown in the drawings. The portions of the flanges 18, forming the top and side rails 95 of the ice-intake opening proper, are offset from the corresponding portions of the wall opening 11, so as to provide spaces for receiving the outwardly projecting flanges 35 of said frame bars. Said flanges 35 overlap 100 the flanges 18 and 24, and are secured thereto by rivets or bolts 36. The other flanges 37 of said bars overlap the rear face of the ice-box about but beyond the edges of the rear door 31, and are secured to said ice- 105 box by fastening screws 38.

In a majority of cases, the back porch is exposed to the sun during some period of the day, and during that time the sun rays beat against the door 21, with the attendant 110 result that the door 21 becomes materially heated. Consequently, the heat radiating from said door aids in melting the ice in the ice-box. To prevent this, we provide on the rear face of said door 21 a heat-insulating 115 material 39, the latter being of any well known substance and carried by the door in a casing 40 secured to the rear side thereof for that purpose. The portion of the front face of the panel 17 below the door 21 is 120 offset or countersunk inwardly so as to avoid a bulky appearance being given to the panel as a whole, and such portion of said panel is insulated from the part of the ice-box there- 125 behind by a heat-insulating material 41, secured to the back of the panel by a cas- 130 ing 42.

When the wall 10 is provided with a window 13, as shown in Figs. 1 and 2, it has been the practice heretofore to set a stone 130

window sill in the wall and place the bottom rail of the window frame on the top of the stone sill. As stone sills are usually somewhat thick, it follows that the inside 5 sill of the window is raised considerable above the top of the ice-box. To avoid this objection, we omit the stone sill and use in place thereof a cast metal sill 43, which of course can be made considerably thinner 10 than the stone sill, yet possess all the strength thereof. The bottom rail of the window frame is thus lowered considerably, when compared with the stone sill construction, and, consequently, the bottom of the 15 window frame is brought closer to the top of the ice-box, thus making it possible to use a larger window than heretofore. The metal sill 43 is inclined outwardly and downwardly, so as to shed water, and is 20 provided in its under side with a downwardly opening groove 44 for the reception of the upper edge of the flange 19, thus causing the latter to act as a means for locking the sill in place.

25 In practice, the combined panel and door frame 17 are made complete before being sent to the building for installation in the wall thereof, the latter being provided with the necessary number of ice-intake openings 30 11 during the course of the construction thereof. The outer door 21 may also be mounted in the panel 17 before the latter is installed in the building wall. The locking mechanism, if used, may also be applied to the door 21 and panel before the 35 latter is installed in the building wall. In short, the panel and all its parts may be complete and assembled before installation in the wall. Of course the ice-box is secured 40 to the frame 34 after the complete panel is installed in the wall, but the frame 34 is applied to the panel before its application to the wall opening 11. By the construction shown and described, it is possible to 45 further standardize building construction, as the openings 11 may all be made of the same size and of such a size as to receive the standard sized panels 17. Then again, by providing a combined metal panel, door 50 frame, and outer door for an ice-intake opening, the objectionable features so apparent to wood lined openings and wooden outside doors therefor are fully and completely eliminated. Then again, the structural 55 cost is materially reduced, as wooden doors and door frames are not required, and further because a portion of the masonry work in connection with each ice-intake opening is materially reduced, thus producing 60 a considerable saving in both labor and material, when considered in connection with an apartment building having a large number of apartments therein. Other and further advantages of our invention will be

readily apparent to those skilled in the art 65 to which our invention appertains.

Although we have shown and described in detail herein a structure embodying the features of our invention, yet it is to be of course understood that the details of construction and arrangement of parts shown may be changed and variously modified without departing from the spirit and scope of our invention, and we do not wish to be limited to the details of construction and arrangement of parts illustrated, except as pointed out in the annexed claims.

We claim as our invention:

1. A metal panel of the character described, having two integral marginal flanges completely surrounding the same, one marginal flange extending outwardly from the body of the panel and adapted to bear against the front face of a building wall, and the other marginal flange extending inwardly from the rear face of said panel at the base of the outwardly extending marginal flange and being arranged at substantially right-angles thereto, said panel being provided in the upper portion thereof 80 with a doorway extending transversely therethrough, a door for closing said doorway, and heat insulating means mounted on the rear face of that portion of said panel below said doorway. 95

2. A metal panel of the character described, having two integral marginal flanges completely surrounding the same, one marginal flange extending outwardly from the body of the panel and adapted to bear against the front face of a building wall, and the other marginal flange extending inwardly from the rear face of said panel at the base of the outwardly extending marginal flange and being arranged at 100 substantially right-angles thereto, said panel being provided in the upper portion thereof with a doorway extending transversely therethrough, a door for closing said doorway, and heat insulating means mounted on 110 the rear face of said door and the rear face of that portion of said panel below said doorway.

3. A metal panel of the character described, having two integral marginal flanges completely surrounding the same, one marginal flange extending outwardly from the body of the panel and being substantially flush with the outer face thereof and adapted to bear against the front face 115 of a building wall, and the other marginal flange extending inwardly from the rear face of the panel at the base of the outwardly extending marginal flange and being arranged at substantially right-angles 120 thereto, said panel being provided in the upper portion thereof with a doorway extending transversely therethrough, and por-

tions of said inwardly extending marginal flange forming the top and side rails of said door-way, said panel being provided with an intermediate flange integral with 5 the body of the panel and extending inwardly from the rear face thereof and forming the bottom rail of said door-way, and a door mounted in said door-way.

In testimony that we claim the foregoing

as our invention, we affix our signatures in 10 the presence of two witnesses, this 29th day of May, A. D. 1917.
